(57) **CLAIM**

The ornamental design for a draining soap dish, as shown.

DESCRIPTION

FIG. 1 is a front elevation view thereof.

FIG. 2 is a right side elevation view, the left side being a mirror image thereof.

FIG. 3 is a back elevation view thereof.

FIG. 4 is a top plan view thereof.

FIG. 5 is a top, front, right perspective view thereof.

FIG. 6 is a top, back, left perspective view thereof.

FIG. 7 is a bottom, front, right perspective view thereof.

FIG. 8 is a bottom, back, left perspective view thereof; and, FIG. 9 is a bottom plan view thereof.

The claimed draining soap dish is used to hold a bar of soap at a sink, in a shower, or on a tub, while keeping the soap from sitting in any amount of water.
